UNITED STATES PATENT OFFICE.

CHARLES KAUFMANN, OF SANTA ANA, CALIFORNIA.

LAMP AND LAMP-SUPPORT.

1,164,358.

Specification of Letters Patent. Patented Dec. 14, 1915.

Application filed July 7, 1915. Serial No. 38,433.

To all whom it may concern:

Be it known that I, CHARLES KAUFMANN, a citizen of the United States, and a resident of Santa Ana, in the county of Orange and 5 State of California, have invented certain new and useful Improvements in Lamps and Lamp-Supports, of which the following is a specification.

My present invention relates generally to 10 lamps, and more particularly to lamps and the supports thereof especially adapted for use in connection with automobiles, motorcycles, canoes, launches, and the like, my object being to provide a simple, strong, and 15 durable arrangement wherein the lamp proper may be removed from its support and utilized as a spot light in case of trouble.

A further object of my invention is to 20 provide a lamp of this character wherein the internal parts are effectively protected against the ingress of dirt, dust and other extraneous matter.

A further object of my invention is to 25 provide a lamp of this character wherein the light bulb may be readily and quickly adjusted to the proper focus and maintained at this point.

Other objects of my invention residing 30 more particularly in the details of construction of the various parts included therein, will be better understood from the following description of these details, reference being had therein to the accompanying drawings, 35 forming a part of this specification, and in which—

Figure 1 is a perspective view illustrating the practical application of my improved lamp to the windshield of a motor vehicle, 40 the lamp proper being turned to one side to better illustrate its practically universal support. Fig. 2 is a perspective view illustrating the practical application of the invention and showing the lamp proper removed 45 and utilized as a spot light in case of trouble. Fig. 3 is a detail vertical section taken there-through substantially on line 3—3 of Fig. 1. Fig. 4 is an elevation in the same position as Fig. 1, with certain of the parts broken 50 away and in section to better illustrate their detail connection. Fig. 5 is an enlarged detail section illustrating the dust-proof connection between the reflector housing, reflector, and lens. Fig. 6 is a detail horizontal 55 section taken substantially on line 6—6 of

Fig. 4. Fig. 7 is a detail perspective view of the reflector removed. Fig. 8 is a similar view of the handle with its cap removed, and Fig. 9 is another detail section illustrating the light bulb and its socket.

Referring now to these figures, and more particularly to Fig. 4, it will be seen that I provide a handle A having an intermediate depending post A', the handle A normally extending in horizontal position in use, and being tubular in form with a concave rear end A² having threads for the reception of a cap B having a concaved inner face abutting the concaved end A² of the handle and provided with threads internally thereof to engage the threads of the handle end just mentioned, so as to bring the concaved faces into opposition, thus providing a cavity for the reception of a packing C, the function of which is to closely surround the light cord D and prevent the entrance of dirt, dust, and extraneous matter within the handle A. The opposite end of the handle A is externally threaded as best seen at A³ in Fig. 8, for the reception of the internally threaded 70 rear tubular extension E' of the reflector housing E, the enlarged outer end of which is provided with a threaded portion E² adjacent its annular shoulder E³, both as best seen by reference to Fig. 5. The shoulder 75 E³ receives a packing strip F against which is seated the outer flange end G' of the reflector G, and the threaded portion E² is engaged by the internally threaded ring H having a flange H' by means of which the 80 lens I is firmly held in position with its edge against the flange G' of the reflector, a packing F' being interposed between the flange H' and the lens I whereby, with the packing 85 F and the screw connection between the parts, a thoroughly dust and dirt proof joint is formed, excluding all extraneous matter 90 from the interior of the lens.

The reflector G has a rear tubular extension G² best seen in Fig. 7, which, as shown 100 clearly in Fig. 4, extends within the forward end of the handle A and is provided with an aperture g through which a clamping screw J threaded through the handle A intermediate its ends, may project into engagement 105 with the socket K of the light bulb whereby to thus secure the socket K and the light bulb K' carried thereby, in adjusted position and at the proper focusing point within the reflector. The light cord D extends 110

from the rear of the socket K and through the rear stuffing box of the body A as before described.

- 5 The post A' depending from the handle A is provided at its lower end with a smooth cylindrical portion A⁴ below an intermediate annular shoulder A⁵, this smooth cylindrical portion A⁴ being adapted to extend within a split upright bearing L' of a swiveled supporting block or member L, the split portions of this bearing L' being connected by a clamping screw M by means of which the lamp may be secured in adjusted position around the vertical longitudinal axis of the 10 post A'. Upon loosening of the clamping screw M, however, the lamp may be either further adjusted around the axis just mentioned, or wholly removed from the supporting member L for use as a spot light in 15 case of trouble, as plainly seen by reference to Fig. 2, and in this event considerable length of light cord D is necessary. When so used it will be seen that the handle A with its integral depending post A', may be 20 firmly grasped in the hand as the light is manipulated from one part to another of the vehicle or boat in connection with which my improved lamp is mounted, without danger of dropping and breaking the same.
- 25 30 The swiveled supporting member L has a split horizontal bearing L², at one side of its vertical bearing L' before mentioned, this split horizontal bearing L² being joined by a clamping bolt N and engaging the outer 35 cylindrical extension O' of a bracket O having inner bent and vertically spaced extensions O² opposing the similarly bent and vertically spaced extensions P' of a U-shaped clamping frame P provided with 40 projections P² engaging the bracket O and further connected to the bracket by clamping bolts and nuts Q extending through the clamping frame P and the bracket O at points between the projections P² and the 45 bent clamping extremities P', all as best seen by reference to Figs. 1 and 6. Thus by manipulation of the clamping bolt N, the swiveled supporting member L may be shifted vertically around the axis of the extension O' of the bracket O, so that the lamp 50 may be adjusted to either inclined or vertical position. In adjusting the lamp upon the vertical axis of the post A', however, it is to be noted that the outer portion O' of 55 the bracket is substantially above the plane of its inner clamping end for engagement with various portions of a vehicle or boat, as for instance, the frame of an automobile windshield as indicated at R in Figs. 1, 2, 60 and 4, thus permitting the lamp to be swung completely around, throughout a full circle. It will furthermore be seen that the several parts of my improved lamp are capable of ready and quick adjustment, are susceptible 65 of practical and effective use for the pur-

poses mentioned, and are at the same time simple, inexpensive, and durable in use.

I claim:—

1. A lamp of the character described including a tubular handle having a post depending therefrom, and having a stuffing box at one end through which a light cord is adapted to extend, a reflector housing having a threaded connection at its inner end with the opposite end of said handle and having a threaded outer portion, a swiveled supporting member in which the lower end of said post is adjustably and removably held, a reflector mounted within said housing and having a tubular inner extension projecting within the handle and provided with an aperture, a lens, a clamping ring for the lens having threads engaging the outer threaded portion of the reflector housing, a bulb socket extending through the tubular inner extension of the reflector and to which the light cord is connected, a clamping screw threaded through the handle and extending through the aperture of the reflector extension whereby to engage and adjustably hold the said bulb socket, and a bracket upon which the said supporting member is carried.

2. A lamp of the character described including a tubular handle, having a post depending therefrom and having a stuffing box at one end through which a light cord is adapted to extend, a reflector housing having a threaded connection at its inner end with the opposite end of said handle, a swiveled supporting member in which the lower end of said post is adjustably and removably held, a reflector mounted within said housing and having a tubular inner extension projecting within the handle and provided with an aperture, a bulb socket extending through the tubular inner extension of the reflector and to which the light cord is connected, and a clamping screw threaded through the handle and extending through said aperture of the reflector extension whereby to engage and adjustably hold the said bulb socket.

3. A lamp of the character described including a tubular handle having a stuffing box at one end through which a light cord is adapted to extend, a reflector housing having a threaded connection at its inner end with the opposite end of said handle and having a threaded outer portion, a reflector mounted within said housing and having a tubular inner extension projecting within the handle and provided with an aperture, a lens, a clamping ring for the lens having threads engaging the outer threaded portion of the reflector housing, a bulb socket extending through the tubular inner extension of the reflector and to which the said light cord is connected, and a clamping screw threaded through the handle and extend-

ing through said aperture of the reflector extension whereby to engage and adjustably hold the bulb socket.

4. A lamp of the character described including a tubular handle having a stuffing box at one end, a reflector housing having a threaded connection at its inner end with the opposite end of said handle, a reflector mounted within said housing and having a tubular inner extension projecting within the handle and provided with an aperture, a bulb socket extending through the tubular inner extension of the reflector and having a flexible cord leading therefrom through the handle and through the stuffing box thereof, and a clamping screw threaded through the handle intermediate its ends and extending through the aperture of the

said reflector extension whereby to engage and adjustably hold the said bulb socket.

5. A lamp of the character described including a handle having a depending post provided with a smooth cylindrical bearing, a bracket having a clamp at its inner end, and a reduced cylindrical extension at its outer end elevated above the clamp, a supporting member having a split bearing disposed on the said bracket extension, and a second split bearing adjacent, and at right angles to, the first bearing, and in which the said bearing of the handle post is disposed, and clamping members for said split bearings whereby to securely hold the parts in adjusted position.

CHARLES KAUFMANN.
